UNITED STATES PATENT OFFICE.

JAMES ROPER, OF LAWRENCE, MASSACHUSETTS.

IMPROVEMENT IN STEAM-TRAPS.

Specification forming part of Letters Patent No. 147,286, dated February 10, 1874; application filed November 26, 1873.

To all whom it may concern:

Be it known that I, JAMES ROPER, of Lawrence, of the county of Essex and State of Massachusetts, have invented a new and useful Improvement in Steam-Traps; and do hereby declare the same to be fully described in the following specification and represented in the accompanying drawings, of which—

Figure 1 is a top view, Fig. 2 a longitudinal section, and Fig. 3 a transverse section, of a steam-trap constructed in accordance with my invention, the object of the apparatus being to discharge from a radiator or vessel containing steam water resulting from condensation of steam, and this without allowing of the escape of steam with the water while being discharged.

In the drawings, A is an induction and C an eduction tube, they being equal in diameter and arranged with their axes in one straight line. The bores of the tubes are closed at the inner ends of the two tubes, as shown at c, such ends being connected together. On the said tubes a hollow globe or vessel, G, is arranged, as shown, and provided with stuffing-boxes d d, so as to enable it to turn steam-tight on the two tubes. From the lower end of the vessel an arm or rod, D, extends and carries an adjustable counterbalance-weight, E, provided with a screw, e, for fixing it to the arm. To the opposite end of the globe or vessel G a faucet, H, is fixed. From that part of the induction-tube A which is within the globe G a pipe, B, is extended, as shown in Figs. 2 and 3, and is curved upward, as represented in the latter of said figures. The pipe B opens out of the pipe A, and is open at both ends. Furthermore, in that part of the eduction-pipe C which is within the vessel G there is made transversely a small hole, a, and there is placed in the vessel, as shown, and upon the educt C, a curved valve, F, which is fastened to the vessel G, so as to move with, and be moved by, it in a manner to open and close the hole a.

If we suppose the pipe A to lead from the place of discharge of the water from the radiator, or other article containing steam, and to be relieved of the water of condensation, and the apparatus is to be arranged so that while the axes of the tubes A and C shall be

horizontal, the axis of the rod D and the vessel G shall be inclined to the horizon at a proper angle, the apparatus or steam-trap will be in a condition for operation.

By curving the tube B, in manner shown, such tube, besides performing its other function or functions, serves as a stop to determine the extent of movement of the globe G in one direction.

Such water as may escape from the radiator will flow into and through the pipes A B, and thence into the vessel G; and, after enough of it may have accumulated in the vessel sufficiently to overcome the gravity of the weight E, the vessel G will descend and turn upon two pipes, A C, and at the same time turn the valve F upon the pipe C, and more or less uncover the opening a, and thereby permit the water to escape through it into the pipe C, by which such water will be discharged.

The faucet H serves to enable any air that may gather in or be in the globe G to be discharged therefrom by steam let into the vessel through the pipes A B.

I do not claim a steam-trap made as described and shown in the United States Patent No. 19,757, which, though analogous to my improved steam-trap, differs therefrom in important particulars, viz., in the application of the valve, and the pipe extended within the balanced vessel. In the trap shown in the said patent, the pipe is fixed to and moves with the vessel; whereas in my trap the curved pipe B does not move with the vessel, but is stationary and extends from the induct-pipe A, and serves not only to convey water into the vessel, but as a stop to arrest the movement of the said vessel; whereas the pipe in the trap shown in Patent No. 19,757 is a waste-pipe or educt attached to, and moving with, the vessel in which it is placed, and operating in no respect as a stop to arrest the movement of the vessel. Furthermore, in my trap the valve F is separate from the vessel G, and fixed to it by a screw, as shown. This admits of the valve, as it may wear, being set up to its seat, and also a new valve being substituted, as occasion may require. When the escape-valve is a part of the revolving chamber, or one piece with it, the valve cannot be

adjusted to allow for its wear. It will, therefore, be seen that my separate valve, fixed by means as set forth, has advantages over a valve in one piece with the rotary chamber.

I therefore claim—

1. In the steam-trap, as described, the tube B, fixed to the induct-tube A, and extended therefrom into the counterbalanced vessel G, essentially as represented, in combination with such vessel, its valve F, and the eduction-tube C, provided with the opening *a*, all arranged

with such tubes, A and B, substantially as specified.

2. The separate valve F, applied to the hole *a* of the eduction-tube C, and arranged within and fixed to the vessel G by one or more screws, all being as represented.

JAMES ROPER.
